UNITED STATES PATENT OFFICE.

FRED R. SEIDENSTICKER, OF WEST MERIDEN, CONNECTICUT, ASSIGNOR
TO BRADLEY & HUBBARD MANUFACTURING COMPANY, OF SAME PLACE.

DESIGN FOR A LAMP-STANDARD.

SPECIFICATION forming part of Design No. 11,829, dated June 22, 1880.

Application filed May 10, 1880. Term of patent 7 years.

To all whom it may concern:

Be it known that I, FRED R. SEIDENSTICKER, of West Meriden, in the county of New Haven and State of Connecticut, have 5 invented a new Design for Lamp-Standard; and I do hereby declare the following, when taken in connection with the accompanying drawing and the letters of reference marked thereon, to be a full, clear, and exact description 10 of the same, and which said drawing constitutes part of this specification, and represents a face view.

This invention relates to a design for lamp-standards and similar uses, and particularly 15 to the base portion; and it consists in the form and ornamentation of the base, as shown in the accompanying illustration and hereinafter described.

The principal or lower section of the base consists of a plane surface, *a*, with the sides *b* above inclined inward, the inclined surfaces representing a sunken panel, with a series of inverted heart-shaped figures in said panel, with a tongue between the said figures, all as shown in the accompanying illustration. 25

I claim—

The design for base, consisting of the plane surface *a*, with inclined surface *b* above, showing a sunken panel ornamented by a series of inverted heart-shaped figures, with a tongue 30 between the said figures, as described, and shown in the accompanying illustration.

FRED R. SEIDENSTICKER.
